UNITED STATES PATENT OFFICE

2,037,214

TELEPHONE SYSTEM

Thomas F. Crocker, Chicago, Ill., assignor to Associated Electric Laboratories, Inc., Chicago, Ill., a corporation of Delaware

Application July 5, 1934, Serial No. 733,762

13 Claims. (Cl. 179—51)

The present invention relates in general to telephone systems, but is particularly concerned with the provision of improved night alarm, line terminating, busy test, and cord circuits of a 5 manual telephone system.

In the customary night alarm circuits heretofore employed the line lamps have been actuated in a circuit including an alarm control relay. It has always been a problem to keep this 10 relay in proper adjustment, owing to the fact that in wet weather the accumulated line leakage through the line lamps often becomes sufficient to operate the relay. When the relay is more stiffly adjusted it operates satisfactorily until the line leakage again decreases to a point 15 where the current flow increase effected by the initiation of a call is insufficient to operate it. It then becomes necessary to readjust the relay to meet the new condition.

20 One feature of the invention has to do with the provision of a night alarm circuit wherein a gradual variation in line leakage cannot affect the proper operation of the alarm relay, and wherein cross-talk between calling subscribers 25 waiting for the operator is positively prevented.

Another feature has to do with the provision of an improved convertible line equipment, i. e., equipment which may be originally employed for serving a local battery line and may later be 30 readily converted to serve a common battery line.

The line terminating equipment for common battery lines of a multiple type switchboard, when busy, are so characterized by the presence 35 of ground potential on the sleeves of their multiple line jacks, whereas in the line terminating equipment of local battery lines battery potential is placed on the sleeves of the jacks of such lines.

40 A still further feature of the present invention has to do with the provision of means whereby the operator receives the same indication irrespective of the type of line being tested.

Other features have to do with the provision 45 of a very simple form of cord circuit.

The invention is illustrated in two sheets of drawings comprising Figs. 1 and 2, respectively, which, when Fig. 1 is placed immediately over Fig. 2, diagrammatically show sufficient circuits 50 and apparatus to enable the following description of the various features of the invention to be readily understood.

In Fig. 1 is shown a cord circuit C with an associated operator's telephone circuit OTC. This 55 figure also shows non-multiple and multiplied

line terminating equipment for local and common battery lines.

Fig. 2 also shows other non-multiple and multiple line terminating equipment for local and common battery lines. This figure also shows, 5 within the dashed line rectangle, the novel night alarm equipment employed.

When a call is initiated at a local battery telephone, having its line terminating in local battery line equipment LB1 the current generated by the magneto of telephone T1 passes through contacts 2, the lower winding of relay 1, the contact and ring element of jack J1, over the other side of the subscriber's line. The contacts 3 of relay 1 make before contacts 2 break 15 and complete a locking circuit for relay 1. This circuit extends from the grounded side of the exchange battery, through the upper winding of relay 1, the Lamp L1, conductor 50 and through lower contacts of the night alarm key NK to the ungrounded side of the exchange battery. If the key NK is in operated position the operating path includes the primary windings of the repeating coil RC.

The answering and calling ends of the cord 25 C are symmetrical except that provision for ringing out over the calling end only of the cord is provided. To answer the call the operator inserts the plug P1 of cord C into the jack J1. The operating and holding paths through the 30 winding of relay 1 are thereby interrupted and the relay restores. The lamp L1 is accordingly extinguished and the upper conductor of the line is again connected to the tip side of the jack. The operator may now actuate the combined 35 listening and ringing key K to listening position and converse with the calling subscriber.

If the calling subscriber desires a connection with another local battery telephone, the telephone T2, for example, the operator inserts the 40 plug P of the cord in jack J1. This effects the removal of the winding of the line drop D3 from in bridge of the associated line and the connection of the tip and ring conductors of the cord thereto. The operator may now operate her key 45 K to ringing position to manually signal the called station.

None of the relays of the cord circuit are actuated in the connection described. Since this is the case, the supervisory drop SD in the cord 50 circuit remains in bridge of the ring and tip conductors thereof and may be operated by current generated by the magneto of either of the connected stations to signal the operator.

The line terminating equipment LB4 is like 55

- that of LB3 except that it is there shown as employed in a multiple type switchboard. Full metallic lines such as employed to connect station T1 with LB3; ground return lines such as 5 L4, or ground return lines such as L5, equipped with a repeating coil when it is necessary to insulate a line on account of excessive noise, may be connected to line terminating equipment such as LB3 or LB4.
- 10 When a line is connected with over a local battery line multiple jack, such as J4, the sleeve terminals of the multiples thereof will be marked as busy by the connection of the ungrounded pole of the exchange battery thereto via either 15 resistance 23 or 24.
- 15 If the calling subscriber at station T1 desires connection with station T2 in lieu of T7 the operator inserts the plug P into the jack J2 of this local battery line. This effects the dis- 20 connection of the lower winding of relay 4 from in bridge of the line and connects the tip and ring conductors of the line with the correspond- 25 ing conductors of the cord. As in the prior example the sleeve of plug P connects the ungrounded pole of the exchange battery to the sleeve terminal of jack J2 and its multiples to mark the line busy. Line equipment LB2 is otherwise like LB1.
- If the subscriber at station T1 desires a con- 30 nection with a common battery station, the station T3, for example, the operator inserts plug P into jack J3, thereby connecting the line conductors of T3 with the tip and ring conductors of the cord and disconnecting the call signal 35 L3 and battery from in bridge of the line. The direct ground potential on the sleeve of jack J3 effects the operation of the front sleeve relay 16. This ground completes circuits through the lower winding of this relay to battery and 40 through the upper winding of this relay, the back contact and armature 14, and through the supervisory call lamp L9 to battery. The relay 16 accordingly operates, at armatures 17 and 18 and their front contacts connects the battery 45 feed relay 13 in bridge of the tip and ring conductors of the calling end of the cord, now connected with the line conductors of station T3; and at its armature 19 removes the supervisory drop from in bridge of the ring and tip con- 50 ductors of the cord and connects the lower winding of the back sleeve relay 10 in bridge of the tip and ring conductors on the answering side of the cord.
- The operator manually transmits signalling 55 current out over the called line by holding key K in ringing position. Upon the response of the called party the relay 13 becomes energized over the called subscriber's loop and at armature 14 60 interrupts the circuit traced through the call supervisory lamp L9 and the upper winding of relay 16. The lamp 9 is accordingly extinguished to advise the operator of the response of the called subscriber.
- When the conversation has been completed and 65 the called subscriber replaces his receiver relay 13 again restores and thereby reestablishes the circuit through lamp L9 which serves to give the operator disconnect supervision. If the local battery subscriber desires to signal the operator he 70 may also do so by operating his magneto. The current generated will flow through armature 19 and its front contact, contacts 12, back contact and armature 8, and the lower winding of relay 10 to the other side of the line. Relay 10 accord- 75 ingly operates, and at armature 11 and its work-

ing contact closes a locking circuit for itself before contacts 12 open. This circuit extends from ground through the upper winding of relay 10, armature 7 and its back contact, the upper break listening contacts of the key K, the front contact 5 and armature 11, and lamp L10 to the ungrounded pole of the exchange battery. The lamp L10 lights over this circuit.

Withdrawal of the plugs P and P' from the jacks J3 and J1 brings about the restoration of 10 the circuits to normal.

The line equipment CB4 is like that of CB3, merely showing the application to a multiple type board. Obviously, when a plug is inserted in one of the jacks of equipment CB4 the sleeve terminals of the associated jacks are grounded 15 to identify the line as being in use.

The operations which ensue following the es- 20 tablishment of a connection from any local bat- tery station to any other common battery sta- tion of the types shown are the same as those just described.

Calls incoming over local battery lines having 25 line terminating equipment such as LB3 are han- dled by the operator in a similar manner to those incoming over equipment such as LB1, except that the conventional drop D3 is employed as a call signal.

When a call is initiated from a common bat- 30 tery station, station T3 for example, the oper- ator inserts plug P1 into jack J3 thereby effect- ing the disconnection of the lamp L3 from in bridge of the line and the operation of the answering sleeve relay 5. Since, as previously stated, both halves of the cord C are symmetri- 35 cal, it will be obvious that the relay 5 will operate over circuits identical to those traced through relay 16. It will further be seen that, since the calling loop is already closed, the answering sleeve relay 10 will operate and prevent the light- 40 ing of answering supervisory lamp L10 at this time.

To complete a connection to a local battery line it will be obvious that the operator inserts 45 the plug P into the jack of such line and operates the key K to ringing position.

When conversation has been completed and the calling subscriber replaces his receiver the battery feed relay restores and establishes the circuit through the lamp L10. The local battery sub- 50 scriber can also effect the operation of lamp L9 in the same manner that L10 was operated when the call originated at a local battery station.

If a connection with another common battery station is desired, station T5 for example, the op- 55 erator inserts plug P into jack J5, thereby con- necting the tip and ring conductors of the answer- ing end of her cord to the line conductors of sta- tion T5 and disconnecting the relay 31 and bat- tery from in bridge thereof. The ensuing opera- 60 tions are the same as those which occur in the es- tablishment of a connection to station T3. Upon completion of the conversation the replacing of the receivers at the respective stations causes lamps L9 and L10 to light up and give the oper- 65 ator disconnect supervision.

Particular attention is now directed to the line terminating equipment CB1, which is like that of LB1 except that the circuits have been slightly changed to convert a former local battery line 70 equipment such as LB1 into common battery line equipment. This has been accomplished by plac- ing a shunt 32 about the break contacts of this relay and by connecting both windings and the ex- change battery normally in bridge of the line. 75

When a call is initiated over the line terminating in equipment CB1 the relay 31 operates over the closed line loop to effect the lighting of its line lamp, and is disconnected from the line by the insertion of a plug in the associated jack J5. Subsequent operations in the establishment of connections between a line terminating in equipment such as CB1 and other lines will be readily understood.

10 When a multiple type switchboard is employed the operator tests the desired line for a busy condition by touching the tip of her calling plug P against the sleeve terminal of the jack of such line located at her position. It will be assumed, 15 for example, that local battery station LB2 is the one with which a connection is desired, and that the line has been taken for use by an operator at the position at which J2' appears. The touching of plug P against the sleeve of jack J2 completes 20 a circuit from the grounded terminals of the exchange battery, through resistance 26, contacts of the operator's battery feed relay 27, the tertiary winding of the induction coil, operated listening contacts of key K, the break contacts 25 controlled by armature 18 of sleeve relay 16, the upper break ringing contacts of key K, the tip of plug P, the sleeve of jack J2, and the sleeve of jack J2' to battery via a resistance such as 23 or 24 of a cord like C employed in the prior connection with the desired line. The click produced in the receiver of the operator's telephone circuit upon completion of the traced circuit advises her of the existing busy condition of the desired line.

30 If a connection with a common battery line is desired the operator makes a like busy test. Since, however, these lines are identified as busy by placing ground potential on the sleeves of their jacks the test circuit includes, at the operator's telephone circuit, resistance 25 and the ungrounded pole of the exchange battery. It will be obvious that when the operator's telephone circuit OTC is to be employed with a non-multiple type board, the testing portion of the circuit may be omitted.

40 When the night alarm key NK is in operated position the connection of the ungrounded pole of the exchange battery directly with the common current supply lead 50 for all line lamp signals of the board is interrupted by the break contacts of this key and accordingly the normal shunt about the primary windings of repeating coil RC is removed.

45 The key NK also at its upper make contacts closes a point in an operating circuit of alarm relay 33, at its middle make contacts closes an obvious circuit including the polarizing winding of relay 37, and at its lower make contacts includes the operating winding of this relay in series with the secondary winding of the repeating coil RC. Under these circumstances when a call is initiated over any line terminating in line equipment employing a lamp-type call signal, the current for operating such signal passes through the primary windings of RC, thereby inducing a momentary surge of current in its secondary winding. This surge of current effects the operation of relay 37. The polarizing winding of this relay is then sufficient to hold the same operated. The 55 relay 37 upon operating completes an obvious circuit for the alarm relay 33. This relay accordingly operates and at its contacts 34 closes the circuit of the night alarm A. The relay 33 also, at contacts 35, opens the operating circuit of relay 37 to prevent its possible reoperation when

key NK is later restored; and at contacts 36 connects the ungrounded pole of the exchange battery to conductor 50 thereby again placing a shunt about the primary winding of the repeating coil RC to prevent other subscribers waiting for the operator, from being able to talk to each other through the inductance otherwise afforded by the primary windings of RC.

5 To restore the night alarm circuit to normal after it has once been operated by the surge of current as described, the operator must restore key NK. Upon restoration of this key the circuit through the polarizing winding of relay 37 is interrupted, causing this relay to restore. The middle make contacts of key NK are adjusted to break 15 first in order to positively prevent a false kick up of relay 37 which otherwise might result if contacts 35 are closed before the middle contacts of NK are opened.

20 When all of the existing calls have been disposed of the operator may again prepare the night alarm circuit by reoperating the key NK.

It will be quite obvious that the initiation of calls over local battery lines equipped with line drops, directly effects the completion of a circuit 25 through the alarm relay 33 in the customary manner. Under these circumstances it will be obvious that the alarm relay restores when all actuated line drops have been restored.

Having described the invention, what is considered to be new and is desired to be protected by Letters Patent will be set forth in the following claims.

What is claimed is:

1. In a telephone subscriber's line terminating equipment a relay having two windings, a jack having pairs of normally closed contacts, a line signal, an operating circuit for said relay including one of its windings and one pair of the normally closed contacts of said jack in series with the other winding of said relay and another pair of contacts of said jack, and a circuit for said signal controlled by said relay. 35

2. In a telephone system, a subscriber's line, a line jack in which the conductors of said line terminate, a two-winding line relay, contacts in said jack through the medium of which one terminal of each of the windings of said relay are connected to the conductors of said line, a source of current connected to the other terminals of the windings of said relay, subscriber actuated means for completing a circuit over said line through said contacts and through both windings of said relay to operate the same, and a line signal controlled by said relay. 45

3. In a telephone subscriber's line terminating equipment, a relay having two windings, a call signal, a jack, an operating circuit for said relay including contacts of said relay, one of its windings, and contacts of said jack, and a locking circuit for said relay including said call signal in series with other contacts of said relay, other contacts of said jack and its other winding. 50

4. In a telephone system, a calling line, line equipment at a central exchange in which said line terminates, a line signal associated with said equipment, an operating circuit for said signal closed by said equipment in response to the initiation of a call over said line, a signal auxiliary to said line signal, a relay for controlling the operation of said auxiliary signal, and means included in the operating circuit of said line signal circuit for inducing a current flow in said relay sufficient to operate it. 65

5. In a telephone system, a calling line, line 70

- equipment at a central exchange in which said line terminates, a line signal associated with said equipment, an operating circuit for said signal closed by said equipment in response to the initiation of a call over said line, a signal auxiliary to said line signal, a relay for controlling the operation of said auxiliary signal, means included in the operating circuit of said line signal circuit for momentarily inducing a sufficient current flow 10 through said relay to operate it, and means for thereafter maintaining said relay operated until the call is answered.
6. In a telephone system, calling lines, a night alarm signal, circuit arrangements for controlling 15 said signal including an electro-polarized relay; a repeating coil having its secondary winding included in circuit with the operating winding of said relay, line signals of said system supplied with operating current through the primary winding of said induction coil when any of said lines initiates a call, the induced current flow in the secondary resulting from the initial current flow in the primary when any line of the system initiates a call, being sufficient to effect the actuation 20 of said relay, a second relay having an operating circuit closed by said first relay, contacts on said second relay for interrupting the operating circuit of said first relay, other contacts on said second relay effective to actuate said night 25 alarm signal; and further contacts on said second relay for short circuiting the primary winding of said repeating coil to prevent subscribers on other calling lines, waiting for the operator, from talking to each other through the inductance afforded 30 by the primary winding.
7. In a telephone system, calling lines, a night alarm signal, circuit arrangements for controlling said signal including an electro-polarized relay; a repeating coil having its secondary winding included in circuit with the operating winding of said relay, line signals of said system supplied with operating current through the primary winding of said induction coil when any of said lines initiates a call, the induced current flow in 35 the secondary resulting from the initial current flow in the primary when any line of the system initiates a call, being sufficient to effect the actuation of said relay, a second relay having an operating circuit closed by said first relay, and means controlled by said second relay for actuating said night alarm signal and for preventing calling subscribers from talking to each other through the inductance afforded by the primary winding of said repeating coil.
- 55 8. In a line equipment for a subscriber's line of a manual telephone system, a double wound relay having an operating circuit including a source of current and its two windings in series with the conductors of a subscriber's line when such line is equipped with a common battery type of telephone; including break contacts of the relay and one of its windings in series with the conductors of a subscriber's line when such line is equipped with a magneto type of telephone; 60 and a locking circuit for said relay, when employed with a line equipped with a telephone of the latter type, including a pair of contacts thereof, the line signal of such line and a source of current.
- 70 9. In a telephone system, calling lines, line signals individual to the respective calling lines, a common operating circuit path for said signals with individual branches, means controlled over said lines upon initiation of calls thereover to 65 close their respective signal circuits, a relay having its operating winding inductively connected to said common operating current path and operated by an induced current resulting from any calling line initiating a call, means for thereafter maintaining said relay operated independently of 75 said inductive connection, and means controlled by said relay for actuating a signal to notify an operator that at least one of said lines has initiated a call, and for also disabling the inductive relationship between said common circuit path and said relay, thereby preventing subscribers of other calling lines from communicating with each other through this otherwise inductive circuit.
10. In a telephone system, local and common 15 battery subscribers' lines terminating in multiple line jacks at a central exchange, a universal cord circuit for establishing connections between said lines, means for placing battery potential of one polarity on the sleeves of the jacks of certain of 20 said lines to mark them as busy, means for placing potential of the opposite polarity on the sleeve of the jacks of other lines to mark them as busy, and means in said cord circuit responsive to in like manner advise an operator of such busy condition when the tip of a plug of said cord is touched against the sleeve of the jack of a busy line.
11. In a night alarm circuit for a central exchange, a night alarm signal control relay actuated directly over a circuit including contacts closed by the actuation of a line drop of a magneto line responsive to the initiation of a call over a magneto line; a second relay, for controlling said signal through the medium of said first relay, having a normally energized polarizing winding, and having an operating winding inductively connected in a common operating circuit provided for the line signals of calling lines of the common battery type and operated by current 40 induced in its operating winding responsive to the initiation of a call over a common battery line, and means controlled by the actuation of said first relay for disabling the inductive relationship between said second relay and said common operating path to prevent cross-talk.
12. In a telephone system, a plurality of local and common battery lines terminating in suitable jacks of a telephone switchboard, a cord circuit for establishing connections between said lines, a supervisory signal in said cord normally in bridge 50 of the tip and ring conductors thereof and operable by current generated by either of a pair of connected local battery lines, a pair of lamp signals in said cord, a relay in said cord operated 55 in response to the connection of a local battery line with a common battery line for removing said supervisory signal from in bridge of the tip and ring conductors of said cord, means placed in bridge of the answering end of said cord by said 60 relay controllable by a subscriber of the local battery line for actuating one of said lamp signals, and a relay having means for controlling the other of said lamps placed under the control of a subscriber of the common battery line by the 65 operation of said first relay.
13. In a telephone system, a cord circuit for use in interconnecting local and common battery lines, a supervisory signal normally in bridge of the tip and ring conductors of said cord for use 70 solely by either of the subscribers of a connected pair of local battery lines to signal the operator, a pair of lamp signals in said cord, sleeve and battery feed relays, respectively, in each end of said cord, a circuit for the sleeve relay of one end 75

of the cord completed by the connection of such end of the cord with a common battery line, means actuated by such relay to connect the associated battery feed relay and a source of current in bridge of the common battery line connected with, other means actuated by said relay to remove said supervisory signal from in bridge of the cord and for connecting of the

other battery feed relay in bridge of the far end of the cord, local battery station controlled means for actuating the latter relay, a locking circuit for the latter relay including one of said lamps, such lamp operating over said locking circuit to signal the operator. 5

THOMAS F. CROCKER.
